UNITED STATES PATENT OFFICE.

HARRY E. DEY, OF BROOKLYN, NEW YORK, AND FREDERICK B. GRISWOLD,
OF HARTFORD, CONNECTICUT.

BICYCLE.

SPECIFICATION forming part of Letters Patent No. 485,094, dated October 25, 1892.

Application filed March 5, 1892. Serial No. 423,806. (No model.)

To all whom it may concern:

Be it known that we, HARRY E. DEY, a citizen of the United States, residing at Brooklyn, in the county of Kings and State of New York, and FREDERICK B. GRISWOLD, a citizen of the United States, and a resident of Hartford, in the county of Hartford and State of Connecticut, have invented certain new and useful Improvements in Bicycles, of which the following is a specification, reference being had to the drawings accompanying and forming a part of the same.

Our invention is an improvement in the driving mechanism of bicycles, tricycles, and the like in which the motion of a pedal-shaft is transmitted to that of a driving-wheel.

Heretofore the driving mechanism usually has consisted of a sprocket-wheel on the pedal-shaft geared by a chain belt to another wheel on the driving-axle; but it is well known that the loss of power in such machines is largely due to the friction and loss in the driving-gear. Moreover, it often becomes necessary or desirable to change the relative gear, and this, with the devices in common use, is a matter of no little difficulty and expense. We propose to substitute for the chain belt and sprocket-wheel a rotary engine and a motor carried by the pedal and driving shafts, respectively, and connected by passages or tubes for conducting the liquid from the pump or engine to the motor and back; and our invention resides in the particular construction and adaptation of these devices to the purpose set forth.

In the accompanying drawings, Figure 1 is a side elevation of a bicycle to which our invention is applied. Fig. 2 is a longitudinal section of our improved driving mechanism on line $x-x$ of Fig. 3. Fig. 3 is a horizontal section of the same on line $y-y$ of Fig. 2. Fig. 4 is a section of the pump or engine on line $z-z$ of Fig. 3. Fig. 5 is an enlarged view in central section of a valve mechanism.

The invention is applicable to any form of safety-bicycle or tricycle or such machines as employ the ordinary chain belt and sprocket-wheels, and is illustrated herein as applied to a well-known form of safety-bicycle.

A is the frame of the machine, and B the fork, in which is mounted the front wheel C.

The pedal-shaft D and driving-axles E are mounted in the usual manner in proper bearings in the frame. The pedal-shaft passes through a closed casing F, but eccentrically to the same, and carries a disk G. A piston or vane H passes through the shaft and disk and is movable through the same, constituting with the casing an ordinary form of rotary pump or engine.

The casing F is connected by means of induction and eduction pipes K K with a similar casing F' on the axle of the driving-wheel, and in the latter there is contained a rotary disk G' and piston H', similar to those described, and constituting a rotary motor which is driven by the fluid forced through the casing and pipes K K by the operation of the pump on the pedal-shaft.

The two pumps or engines may have any given relations to one another; but for the purposes of varying the relations between the two we provide an additional but smaller chamber or casing L around the pedal-shaft and employ a second disk M and a piston N therein, mounted on the shaft in the same manner as the others.

The space in casing or chamber L is shut off from that in the main casing by the disk G, and branch pipes O O from the main induction and eduction pipes are connected with it.

There is a by-pass P in the side wall of the casing L, containing a gate-valve which when open permits the fluid, under the action of the piston N, to circulate around the disk M, but when closed causes the smaller pump to act in conjunction with the larger and produce a stronger flow or circulation of fluid through the motor. Thus in driving a bicycle where power rather than speed is desired, the by-pass P is opened, so that only the main pump works; but when increased speed is desired the valve in by-pass P is closed, thus producing a greater flow by the combined action of both pumps that drives the motor on the driving-shaft at a higher speed. In order to check the flow of fluid through the small pump, except when the same is in operation, an automatic stop-valve p is placed in the eduction pipe or port to prevent backflow.

We have provided special means for con-

trolling the action or operation of the valve in the by-pass P. The valve itself consists of a gate n, carried by a disk o in a cylindrical casing m, said gate extending through a slot in the side wall of the casing L, and being adapted to open and close the by-pass, according to its position. The valve is acted upon by a spring c, that keeps it normally open, and is closed by the pressure of a liquid above it, produced by the pressure of a bulb R, connected with the valve-chamber by a pipe or tube S. The bulb R may be placed in any convenient position to be reached by the rider and may constitute one of the handles of the yoke. 15 We also propose to dispense with the usual form of brake and to employ a gate-valve in one of the pipes K, which valve is operated by liquid-pressure in the same way as the first. In Fig. 5 the details of this valve are shown 20 in section. b is a casing which contains the valve, the main portions of which are a disk e, working in the cylindrical portions of the casing, and a plate or gate d, passing through slots in the side walls of the eduction-pipe and 25 provided with a circular opening g. The valve is normally held open by a spring f constantly acting upon it. Whenever it is desired to check the speed of the machine, the rider by squeezing the bulb V, which also may be one 30 of the handles, forces the plate d against the spring f and causes it to close to a greater or less extent the eduction-passage, which is open fully only when the hole in the plate d registers with it. As there is no waste of 35 liquid in this apparatus, all portions of the motion-transmitting mechanism being tightly closed, we propose to use oil or glycerine as the transmitting medium.

The invention, in respect to the more general features specified in the claims, is not limited to the particular devices herein described, for it is obvious that without departure from the principle of construction and operation the same results may be secured 40 by many arrangements the well-recognized equivalents, mechanically, of those herein described.

We do not claim as our invention the combination of a pump and motor as a means of transmitting power, broadly; but 45

What we claim as our invention is—

1. The combination, with the pedal-shaft and driving-axle of a cycle, of a rotary fluid-motor mounted on the driving-axle, a rotary fluid-pump of variable capacity mounted on the pedal-shaft, and pipes or tubes forming direct passages of communication between the eduction and induction ports of the pump and induction and eduction ports, respectively, of the motor. 55

2. The combination, with the driving-axle and pedal-shaft of a cycle, of a rotary fluid-motor on the driving-axle, a rotary fluid pump or engine having two pistons of unequal capacity mounted on the pedal-shaft, means for

bringing one or both of said pistons into operation, and thereby varying the capacity of the pump, and eduction and induction pipes or passages connecting the motor and pump, as set forth. 70

3. The combination, with the driving-axle and pedal-shaft of a cycle, of a rotary motor mounted on the driving-axle, a rotary pump mounted on the pedal-shaft, pipes or tubes forming direct passages of communication 75 between the eduction and induction ports of the pump and induction and eduction ports, respectively, of the motor, and a brake-valve located in one of said pipes, as set forth.

4. The combination, with the driving-axle 80 and pedal-shaft of a cycle, of a rotary motor on the driving-axle, a rotary pump or engine on the pedal-shaft, eduction and induction pipes connecting the same, a brake-valve located in one of said pipes, a compression-bulb connected with the chamber of said valve and adapted to move and operate the same by the pressure of a fluid contained therein, as set forth. 85

5. The combination, with the rotary motor 90 on the driving-axle, of a pump or engine on the pedal-shaft, consisting of a casing having two compartments or chambers of unequal capacity, eduction and induction pipes between the same and the motor, pistons connected with the pedal-shaft and located in the two chambers of the pump-casing, respectively, a by-pass in one of said chambers, and a valve for controlling the same, as set forth. 95

6. The combination, with the driving-axle 100 and pedal-shaft of a cycle or other vehicle, of a rotary fluid-motor on the driving-axle, a rotary fluid pump or engine connected with the same through eduction and induction pipes, said engine being composed of separate chambers or compartments and pistons or vanes connected with the pedal-shaft and working in the chambers, respectively, a by-pass in one of the chambers, and a valve for 105 controlling the same, as set forth. 110

7. In a bicycle provided with a rotary motor on the driving-axle, a rotary engine of variable capacity on the pedal-shaft, and a series of pipes connecting the same, the combination of a brake-valve in one of the connecting-pipes, a valve for controlling the action of the motor-pistons for varying the capacity of the engine, and compression-bulbs attached to the yoke or handle of the bicycle and connected with pipes or tubes containing a fluid with the said valves, as and for the purpose set forth. 115 120
